UNITED STATES PATENT OFFICE.

JOSEPH K. ALTERS, OF MAIDEN ROCK, WISCONSIN, ASSIGNOR OF ONE-HALF
TO MARONI WARE, OF SAME PLACE.

BUTTON-FASTENING.

SPECIFICATION forming part of Letters Patent No. 271,185, dated January 23, 1883.

Application filed September 18, 1882. (No model.)

To all whom it may concern:

Be it known that I, JOSEPH K. ALTERS, of Maiden Rock, in the county of Pierce and State of Wisconsin, have invented certain new and useful Improvements in Fastenings for Buttons; and I do hereby declare that the following is a full, clear, and exact description of the invention, which will enable others skilled in the art to which it appertains to make and use the same, reference being had to the accompanying drawings, which form a part of this specification, and in which—

Figure 1 is a vertical sectional view of my improved button-fastener. Fig. 2 is a top view of a button provided with the same. Fig. 3 is a vertical sectional view on line $x-x$ in Fig. 2, and Fig. 4 is a plan view of the fastening.

Similar letters of reference indicate corresponding parts in all the figures.

My invention has relation to that class of button-fasteners which consist in a button-shoe disk having prongs on its outer sides adapted to engage within holes of a button and hold it in position on a fabric; and it consists in the improved construction of the same, as herein-after more fully described and claimed.

Heretofore there has been a disadvantage in button-fastenings of this class in their bringing the button and the fabric so close to each other that buttoning was effected with great difficulty, the button pressing flat against the fabric. To avoid this difficulty, I shape the fastening so as to form a sort of shank for the button, thus making the buttoning of it easier.

In the accompanying drawings, the letter A

indicates a metal disk, having a cup-shaped indentation, A', in its center, the bulb thus produced on the other side facing the fabric and raising it, as shown at C. The disk A is cut out of a piece of sheet metal, and has prongs B projecting from its edges and bent at right angles to the disk or plate. These prongs are cut straight on one side, b, and oblique on the other, b', in such a manner that when the prongs are inserted through the fabric and the button and bent over on the upper surface of the button the two points of the prongs will fit alongside each other, and the side b will appear parallel, as plainly shown in Fig. 2 of the drawings.

It will be seen that when the button is fastened on the fabric the bulge A' will raise the fabric on the point of fastening above the level of the surrounding fabric, and in this manner form a shank or stem for the button.

Having thus described my invention, I claim and desire to secure by Letters Patent of the United States—

An improved button-fastening, consisting of the metal plate A, having the central bulge, A', and the edge-attaching prongs b b', of the shape substantially as described, all constructed and adapted for use as specified.

In testimony that I claim the foregoing as my own I have hereunto affixed my signature in presence of two witnesses.

JOSEPH KESSLER ALTERS.
